[57] CLAIM

The ornamental design for a merchandising display rack, as shown and described.

DESCRIPTION

FIG. 1 is a front elevational view of a merchandising display rack, the rear elevational view of which is a mirror image thereof, showing our new design;

FIG. 2 is a leftside elevational view thereof, the rightside elevational view of which is a mirror image thereof;

FIG. 3 is a top plan view thereof;

FIG. 4 is a bottom plan view thereof; and,

FIG. 5 is a perspective view thereof.
